U.S. Cl. D6—186

FIG. 1

FIG. 2

FIG. 3

FIG. 4

FIG. 1 is an isometric view of a stackable rack element for standard magnetic tape cartridges and cassettes showing my new design;

FIG. 2 is a top plan view;

FIG. 3 is a side elevational view; and

FIG. 4 is a bottom plan view.

The design is generally symmetric and the three sides not shown are substantially identical with the sides shown in FIG. 3.

I claim:

The ornamental design for a stackable rack element for standard magnetic tape cartridges and cassettes, as shown and described.
